UNITED STATES PATENT OFFICE.

CHARLES PERCY CHAMBERLIN, OF CALGARY, ALBERTA, CANADA.

KEYLESS AUTO AND ALARM SWITCH.

Application filed May 8, 1920, Serial No. 379,847. Renewed July 27, 1925.

To all whom it may concern:

Be it known that I, CHARLES PERCY CHAMBERLIN, a subject of King George of Great Britain, and residing at Calgary, in the Province of Alberta, in the Dominion of Canada, have invented certain new and useful Improvements in a Keyless Auto and Alarm Switch, of which the following is a specification.

10 My invention relates to improvements in an automobile and alarm switch which can be operated only by an authorized person, and one in which no key is required.

I accomplish this by the device illustrated 15 in the accompanying drawings, in which—

Fig. 1 is a detail view of the switch board showing the contacts and contact makers. Fig. 2 is a wiring diagram showing the arrangements of the various contacts mounted 20 upon the switch board. Fig. 3 is a plan view with the cover removed. Fig. 4 is a view of the push buttons used in operating the switches, as they appear on the dash board. Fig. 5 is a vertical cross section 25 through the device showing a contact maker, and the device for rectifying the circuits, and stopping the ringing of the alarm. Fig. 6 is a broken detail, or fractional view of the alarm contact breaker or circuit rectifier. 30 Fig. 7 is a fractional view of the push button in relation to the release for the circuit rectifier.

Similar characters refer to similar parts throughout the several views.

35 A series of contacts are secured upon a non-conductor base 1, the lower line of contacts *a*, being connected in parallel to a battery *b*. A centre line of contacts *c*, are provided which are in the form of brackets, and 40 for the purposes of illustration, the brackets 2, and 3, are not electrically connected, the rest of the said brackets 4, being connected in parallel to an alarm *d*. Combination contact makers and breakers *e*, and *f*, are 45 mounted in the said brackets, the pivotal points being of conducting material. An upper line of contacts *g*, and *h*, is provided, connected in series to an ignition device *j*, all of which contacts must be made before 50 the ignition circuit is closed. The combination contact makers and breakers, consist of conductor blades 5, pivoted within the brackets 2, 3, and 4, the said blades having secured thereon non-conducting members 6. 55 Secured in the upper end of these non-conductors are contact blocks 7, which engage

the points of the upper line of contacts *g*, and *h*, and make electrical connection there-between. There is no electrical connection at any time between the contacts *g*, and *h*, 60 and either of the lines of contacts *a*, and *c*, the electrical energy flowing to the ignition device through each of the upper line of contacts *g*, and *h*, and the contact blocks 7. When one of the blocks 7 disengages the 65 contact in the upper line, the ignition circuit is inoperative. Operation of the switches is performed by a series of push buttons 8, and 9, mounted through a face plate 10, secured in a convenient place within the car. All these push buttons are of similar construction, and consist of a cylindrical shank *k*, terminating just within the switch box, and having a diametrically smaller rod *m*, provided with a spring *l*, 70 which returns the push button to the normal position. The rod *m*, has a forked end, in which fork a lever *n*, is pivoted, which lever *n*, is held horizontally until such time as it engages the non-conductor *e*, or *f*, by 75 means of a guide *o*, extending horizontally across the box. The operating mediums *f*, are provided with double recesses *p*, so that on depressing the buttons 9, the contacts on the ignition circuit may be made or broken 80 as desired, these buttons being inoperative on the alarm circuit as there is no electrical connection between the centre line of contacts *c*, at 2, and 3, and the alarm circuit. 85 Operating mediums *e*, are provided with 90 only one recess *q*, which is so arranged that upon depressing any of the buttons marked 95 8, contact is broken on the ignition circuit, and made between the centre line of contacts *c*, and the battery contacts *a*, closing the alarm circuit. To stop the alarm and 100 restore the ignition circuit for operation it is necessary to depress a pre-arranged button and while depressed to give it one quarter of one revolution. On doing this the lug *r*, secured to the push button, engages a spring lever *s*, which lever is mounted upon an open ended frame *t*, and normally engages a shoulder upon the guide *o*. The revolving 105 of the button releases the spring lever from such engagement, and a spring *u*, lowers the front of the said frame *t*, and returns the lug *r*, to the normal position. The open ended frame *t*, is pivoted upon the end walls 110 of the box and carries a triangular rod 11, which triangular rod is raised by the releasing of the spring lever *s*, and passing

- behind the projecting ends of the levers 5, below the contacts of the battery circuit *a*, breaks the connection on that line and restores the ignition circuit ready for operation by the correct buttons. While this bar 11, is in the raised position it is impossible to depress any of the push buttons as the ignition contacts having been broken, are retained in the broken position between the bar 11, and the back of the case, and the alarm contacts cannot be made as the levers are retained in the upper contact position in front of the bar 11. This bar 11, operates in slides 12, and has connected to it a pull rod 13, terminating in a button through the bottom of the box, and on pulling this button the bar is lowered, the spring lever 8, reengages the lug on the guide *o*, which is the normal position.
- 20 Any combination of the push buttons may be arranged, the combination shown in the drawings being merely for illustration.
- Having thus described my invention what I claim is—
- 25 1. In an article of the class described, a multiplicity of push buttons mounted through a face plate in the interior ends of

which push buttons are pivoted short arms the said short arms projecting through a guide to engage upon contact makers mounted adjacent to the said arms, a plurality of pivoted members adapted to simultaneously break and make contact upon one way action from the push button, and a pre-determined number of knife switches adapted to 30 make and break contact upon successive operations from the push buttons.

2. In an article of the class described, in combination with a multiplicity of push buttons mounted through a face plate in the interior ends of which are pivoted short arms the said short arms projecting through a guide to engage upon contact makers mounted adjacent the said arms, a plurality of pivoted members adapted to simultaneously 40 break and make contact upon one way action of the push button, and a pre-determined number of knife switches adapted to make and break contact upon successive operations from the push buttons, of an independent means for returning the one way pivoted members to their original position for co-action with the push buttons.

CHARLES PERCY CHAMBERLIN.
